UNITED STATES PATENT OFFICE

HARRISON BAILEY, OF MOUNT CARMEL, PENNSYLVANIA

FOOT REST FOR ACCELERATOR CONTROLS

Application filed April 20, 1928. Serial No. 271,522.

This invention relates to combined foot rests and accelerator controls.

An object of the invention comprehends a locking mechanism adapted to retain the control in a retracted position whereby the 5 accelerator may be rendered inoperative upon application of a motor vehicle service brake.

Another object of the invention contemplates a slide mounting for the foot rest 10 rather than a pivotal one whereby greater ease in the actuation thereof will be experienced.

A further object of the invention consists of a release mechanism for the locking mechanism. 15

An additional object of the invention embodies a tread portion adapted to engage a throttle rod when shifted to occupy its respective positions.

With the above and other objects in view, 20 the invention further consists of the following novel features and details of construction, to be hereinafter more fully described, illustrated in the accompanying drawings and pointed out in the appended claims.

In the drawings:

Figure 1 is a side elevation of the invention as applied for use.

Figure 2 is a longitudinal sectional view 25 taken through the invention when called into use to actuate a throttle rod.

Figure 3 is a sectional view taken on line 3—3 of Figure 1.

Figure 4 is a perspective view of an anchoring plate for the device. 30

Figure 5 is a horizontal sectional view taken through Figure 2 of the drawings with the locking mechanism illustrated in its released position.

Figure 6 is a view similar to Figure 5 taken 40 through Figure 1 of the drawings and illustrative of the locked position of said mechanism.

Figure 7 is a sectional view taken on line 45 7—7 of Figure 1.

Figure 8 is a sectional view taken on line 8—8 of Figure 5.

Figure 9 is a detail sectional view.

Referring to the drawings in detail, where- 50 in like characters of reference denote corre-

sponding parts, the reference character 10 indicates an anchorage or attaching plate of oval shape having openings adjacent the ends thereof to accommodate fastening elements 12 embedded or otherwise connected with a 55 floor board 13 within the driving compartment of a vehicle.

A channel member 14, carried upon one side edge of the plate member 10, is adapted 60 to accommodate the adjacent edge of a supporting plate 15. A curved lip 16, upstanding from the opposed side edge of the plate member 10, is adapted to accommodate and 65 yieldingly engage a correspondingly disposed lip 17 formed upon the adjacent edge of the supporting plate 15, substantially as illustrated in Figure 2 of the drawings. Ears 18, upstanding in parallelism from the opposed side edges of the supporting plate 15, are apertured adjacent the ends thereof to 70 accommodate bolt members 19 and 20. A bearing sleeve 21, carried upon the bolt member 20 and formed as a continuation of the lowermost offset end 22 of an elongated plate member 23, is adapted to establish a pivotal 75 connection between the latter and the supporting plate 15.

A disk member 24, depressed to resemble 80 the general characteristic of a spoon, is disposed in parallelism with the underside of the elongated plate member 23 by fins 25 offset from the uppermost end of the aforementioned plate. The depressed portion of the disk member 24 is adapted to accommodate 85 the head 26 carried upon the adjacent end of a throttle rod 27.

A heel supporting plate 28 is provided upon 90 the lowermost end of a plate member 28' carried upon the upper side of the plate member 23 and having an elongated cut-out portion 29, through which mud and other extraneous matter, tracked into the car upon the operator's feet, may find its way downwardly upon the horizontal floor boards, not shown, within the vehicle. 95

A second plate, such as indicated at 30, mounted upon the upper side of the plate member 23, is provided with downwardly projecting aprons 31 upon the side edges thereof and adapted to accommodate the ad- 100

adjacent portions of the plate member 23 to preserve relative order and relationship of the respective plates.

Ears 32, inwardly and downwardly offset from the aprons 31, are adapted to accommodate a common bolt member 33, which is passed through a sleeve member 34 within the adjacent end of an adjusting plate 35. A companion adjusting plate 36, having pivotal connection with the bolt member 19, as indicated at 37, is provided with channel portions 38 upon the side edges thereof and which is adapted to accommodate and guide the adjacent end of the plate member 35 therebetween.

An elongated slot 39 within the companion plate 36 is adapted to receive a bolt member 40 carried by the plate member 35 to regulate depressing of the throttle rod 27. The adjustment, may, in effect, provide a governor which may be set at low speeds when motor vehicles are initially delivered from factories, whereby the new owner will not be able to race and burn up the motor before the adjustment is altered.

A trip plate 41, having an ear 42 upon the uppermost end thereof, is adapted to be disposed immediately beneath the adjacent end of the plate member 30 in the manner as illustrated in Figure 2 of the drawings. Guide members 43, provided upon the side edges of the trip plate 21, are adapted for reception within portions removed 44 in the aprons 31 of the plate member 30. The guide members 43 furthermore provide the necessary means of attachment for the trip plate 41. A housing 45, carried upon the offset end 22 of the plate member 23, is provided with a reciprocating locking element 46 mounted upon a compression spring 47 and adapted to normally dispose the uppermost portion thereof within the horizontal portion 48 of a substantially T-shaped slot 49 in the plate member 28'. A finger 50, upstanding from the upper edge of the locking member 46, is adapted to engage the underside of the trip plate 41.

In the use and operation of the present invention, the same is first applied to occupy the position as shown in Figure 1 of the drawings.

The depressed disk 24 is adapted to conveniently accommodate the rounded head 26, carried upon the adjacent end of a throttle rod 27.

It is to be noted that a slide mounting is provided rather than a pivot connection, whereby greater ease in the operation of the invention will be experienced.

The invention was primarily designed to limit movement of the throttle rod 27 and the consequent velocity capable of being attained by the vehicle through the connection as provided between the plate members 35 and 36 respectively. The locking mechanism 65 is primarily intended to prevent accidental

acceleration of the vehicle when the vehicle service brake is called into use.

As generally known, accelerators are located in close proximity to the service brakes of motor vehicles in order that the foot may be readily shifted one to another but in spells of excitement, especially when encountering railway crossings and the like or in other instances where the motorist senses impending accident, he may accidentally depress both the service brake and accelerator and does not have time to shift the foot over a bit more to clear the accelerator while depressing the brake pedal.

To actuate the invention from the position shown in Figure 1 of the drawings to occupy the Figure 2 position, the trip plate 41 is depressed by the heel of the operator to release the locking element 46 from the horizontal portion 48 of the T-shaped slot 49 in the plate member 28'.

Depression by the toe of the operator's foot upon the plate member 30 will swing the same downwardly and cause the plate member 23 to be retracted therebeneath and such retraction being commensurate with the particular angle of the throttle rod, whereby binding action of the throttle rod within a usual opening provided in the floor board 13 will not occur.

A retractile spring 51, establishing connection between the plate member 23 and the plate member 35 is adapted to automatically retract the accelerator to occupy an inoperative position when the foot of the operator is released from the plate member 30. Obviously the locking element 46 will again find its way within the portion 48 of the T-shaped slot 49.

The invention would also cut down automobile thefts inasmuch as persons not familiar with the mechanism of the improved type of accelerator would be readily apprehended while experimenting.

The invention is susceptible of various changes in its form, proportions and minor details of construction, and the right is herein reserved to make such changes as properly fall within the scope of the appended claims.

Having thus described the invention, what is claimed is:—

1. A combined foot rest and accelerator control comprising a supporting plate mounted upon the floor boards of an automobile adjacent the throttle rod, a foot engaging portion carried by the supporting plate, and a locking mechanism carried by and operable in conjunction with the supporting plate adjacent the mounting of the latter being adapted to normally sustain the plate member in a normally inactive position.

2. A combined foot rest and accelerator control comprising a supporting plate, a plate member carried by the supporting plate being disposed in juxtaposition to a throttle

rod, a disk member carried by the plate member adapted for engagement with the adjacent end of the throttle rod, a locking mechanism carried by the supporting plate being adapted to normally sustain the plate member in a retracted position, and a trip plate carried by the plate member being adapted to release the locking mechanism when the device is called into use.

3. A combined foot rest and accelerator control comprising an attaching plate, a supporting plate carried thereby, a plate member having pivotal connection with the ends of the supporting plate and disposed in juxtaposition to a throttle rod, a disk member of depressed formation offset from and disposed in parallelism with the plate member being adapted for engagement with the adjacent end of said throttle rod, a spring having connection with the pivot connection to normally retract the plate member to occupy an inoperative position, a locking mechanism for sustaining the plate member against accidental use and displacement, and a trip plate carried by the plate member adapted to release the locking mechanism when the device is called into use.

4. A combined foot rest and accelerator control comprising an attaching plate, a supporting plate carried thereby, a plate member having pivotal connection with the supporting plate and disposed in juxtaposition to a throttle rod, a disk member of depressed formation offset from and disposed in parallelism with the plate member for engagement with the adjacent end of said throttle rod, a second plate member slidably mounted upon the first mentioned plate member, a spring having connection with the first mentioned plate member to induce same to occupy an inoperative position, a locking mechanism for sustaining the supporting plate against accidental use and displacement, a trip plate carried by the second plate member adapted to release the locking mechanism when the device is called into use, and an adjusting means establishing connection between the supporting plate and second plate member to regulate depression of the accelerator.

5. A combined foot rest and accelerator control comprising an attaching plate, a supporting plate carried thereby, a plate member having pivotal connection with the supporting plate and disposed in juxtaposition to a throttle rod, a disk member of depressed formation offset from and disposed in parallelism with the plate member for engagement with the adjacent end of said throttle rod, a second plate member slidably mounted upon the first mentioned plate member, a spring having connection with the first mentioned plate member to induce same to occupy an inoperative position, a locking mechanism for sustaining the supporting plate against accidental use and displacement.

ment, a trip plate carried by the second plate member adapted to release the locking mechanism when the device is called into use, and adjusting plates establishing connection between the supporting plate and second plate member to regulate depression of the accelerator.

6. A combined foot rest and accelerator control comprising an attaching plate, a supporting plate carried thereby, a plate member having pivotal connection with the supporting plate and having a portion disposed in juxtaposition to the throttle rod, a disk member of depressed formation offset from and disposed in parallelism with the plate member for engagement with the adjacent end of said throttle rod, a second plate member slidably mounted upon the plate member, ears extended from the side edges of the second plate member over the side edges of the first mentioned plate member, adjusting plates establishing connection between said ears and the supporting plate to regulate depression of the accelerator, a spring interposed between the adjusting plates and first mentioned plate member to normally induce the latter to occupy an inoperative position, a locking mechanism for sustaining the supporting plate against accidental use and displacement, and a trip plate carried by the first plate member adapted to release the locking mechanism when the device is called into use.

7. A combined foot rest and accelerator control comprising an attaching plate, a supporting plate carried thereby, a plate member having pivotal connection with the supporting plate and disposed in juxtaposition to a throttle rod, a disk member of depressed formation offset from and disposed in parallelism with the plate member for engagement with the adjacent end of the throttle rod, a second plate member slidably mounted upon the first mentioned plate member, ears carried by and projecting from the second plate member beneath the first mentioned plate member, adjusting plates establishing connection between said ear and the supporting plate to regulate depression of the accelerator, a spring establishing connection between the adjusting plates and the first mentioned plate member to normally induce the latter to occupy an inoperative position, a slotted plate including a heel support mounted upon the second plate member, a trip plate having connection with the second plate member and disposed in overlapping relation to the slotted plate, and a locking element mounted upon the first plate member and projecting through the slotted plate adjacent the trip plate.

8. A combined foot rest and accelerator control comprising an attaching plate, a supporting plate carried thereby, a plate member having pivotal connection with the sup-

porting plate and disposed in juxtaposition to a throttle rod, a disk member of depressed formation offset from and disposed in parallelism with the plate member for engagement with the adjacent end of the throttle rod, a second plate member slidably mounted upon the plate member, ears carried by and projecting from the second plate member beneath the first mentioned plate member, 5 adjusting plates establishing connection between said ear and the supporting plate to regulate depression of the accelerator, a spring establishing connection between the adjusting plates and the first plate member 10 to normally induce the latter to occupy an inoperative position, a plate having a T-shaped slot carried upon the second plate member, a trip plate included upon the second plate member and spaced from the slotted plate, a locking element slidably mounted upon the first plate member and normally disposed within the cross portion of the T-shaped slot, and a finger carried by and projecting from one end of the locking element for contacting engagement with the 15 trip plate.
